US0D1017670S

(12) **United States Design Patent** (10) **Patent No.:** **US D1,017,670 S**
(45) **Date of Patent:** **** Mar. 12, 2024**

(54) **GIMBAL OR HANDHELD QUADROPOD**

(71) Applicant: **Xing Wang**, Guanngdonng (CN)

(72) Inventor: **Xing Wang**, Guanngdonng (CN)

(**) Term: **15 Years**

(21) Appl. No.: **29/826,936**

(22) Filed: **Feb. 16, 2022**

(51) **LOC (14) Cl.** **16-05**

(52) **U.S. Cl.**

USPC **D16/243; D16/244**

(57) **CLAIM**

The ornamental design for gimbal or handheld quadropod, as shown and described.

DESCRIPTION

FIG. 1 is a perspective view of a gimbal or handheld quadropod showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view of the gimbal or handheld quadropod in a deployed state.

The broken lines immediately adjacent the shaded areas represent the bounds of the claimed design and form no part of the claimed design. The remaining broken lines illustrate portions of the gimbal or handheld quadropod that form no part of the claimed design.

1 Claim, 3 Drawing Sheets
